UNITED STATES PATENT OFFICE.

JAMES O'BRIEN, OF WANAQUE, NEW JERSEY.

SNOW-GATHERING MACHINE.

Application filed May 13, 1926. Serial No. 108,891.

This invention relates to certain new and useful improvements in snow gathering machines and particularly to the type wherein a motor propelled vehicle carries an endless conveyor with means for delivering snow forwardly of the vehicle onto the conveyor to be discharged at the upper rear end thereof into a trailing vehicle.

A further object of the invention is to provide a snow gathering machine of the type above described wherein adjustable supports are provided for the endless conveyor to vary the elevation of the rear upper end thereof, and further to provide adjustable 15 guard walls positioned at opposite sides of the conveyor and movable with respect to adjustments of the conveyor to prevent the lateral discharge of snow at the point of being deposited upon the conveyor.

With the above and other objects in view that will become apparent as the nature of the invention is better understood, that same consists of the novel form, combination and arrangement of parts hereinafter more fully 25 described, shown in the accompanying drawings and claimed.

In the drawings, wherein like reference characters designate corresponding parts throughout the several views,

Figure 1 is a top plan view of a snow gathering machine constructed in accordance with the present invention,

Figure 2 is a side elevational view of the same showing the side bars supported on the machine frame and the conveyor and upon which the side guards for the conveyor are mounted,

Figure 3 is a detailed sectional view taken on line 3—3 of Fig. 1,

Figure 4 is a detailed sectional view taken on line 4—4 of Fig. 1 showing the adjusting device for varying the elevation of the rear end of the conveyor, and

Figure 5 is a fragmentary side elevational view showing the pivotal mounting of the conveyor upon the machine frame.

Referring more in detail to the accompanying drawings and particularly to Figs. 1 and 2, there is illustrated a snow gathering machine comprising a vehicle frame having side bars 1 preferably of channel line formation as shown in Figs. 3 and 4 connected together at their rear ends by a cross bar and carrying depending journal bearings 2 intermediate the ends and adjacent the forward ends thereof as shown in Figs. 1 and

2 for supporting forward ground wheels 3, the rear end of the vehicle frame 1 being supported by rear ground wheels 4. Side rails 5 are positioned outwardly of the side bars 1 of the chassis frame and are rigidly supported at their rear ends upon the transverse channel iron 6 that is rigidly attached to the side bars 1 of the chassis while the forward ends of the side rails 5 are supported upon the journal bearings 2 for the forward ground wheels 3.

An endless conveyor frame is pivotally supported intermediate its ends upon the side bars 1 of the chassis, the conveyor frame comprising side bars 7 connected together at their opposite ends by cross shafts 8 and 9 as shown in Figs. 2 and 3, the conveyor frame being disposed between the side bars 1 of the chassis frame and the side rails 5 and hinged- 75 ly supported as at 10 upon the chassis frame. A roller 11 journaled on the shaft 8 at the lower end of the conveyor forms a guide for the endless conveyor belt 12, the upper end of the loop thereof passing over the roller 13 upon the cross shaft 9 while one projecting end of the shaft 9 has a sprocket wheel 14 keyed thereto.

The support for the upper over-balanced end of the endless conveyor frame is shown 85 more clearly in Fig. 4 wherein a screw rod 15 having a ball and socket connection 16 at its upper end with the lower side of the conveyor frame is threaded at its lower end through the cross shaft 17 that is journaled 90 at its ends in the side bars 1 of the chassis frame and side rails 5 with the lower end of the screw rod 15 passing through an opening in the cross channel iron 6, the screw rod being provided with a handle 18 by which 95 the same may be operated to effect raising and lowering movements of the rear upper end of the conveyor frame.

The forward lower end of the endless conveyor terminates adjacent the ground line 100 between the side bars 1 and rails 5 while a rotatable snow gathering drum supported on the forward ends of the side bars 1 direct the snow onto the conveyor. The rotatable drum 19 is journaled in depending 105 bracket bearings 20 carried by the forward ends of the side bars 1 and fins or blades 21 extending lengthwise of the drum 19 and outwardly thereof gather the snow and deliver the same onto the endless conveyor 110 belt 12, each projecting end of the shaft 22 to which the drum is keyed being provided

with a sprocket wheel 23 to be driven in a manner presently to be described.

To prevent a lateral displacement of the snow from the conveyor belt 1 at the lower end thereof where deposited by the rotatable gathering drum 19, guide plates 24 are provided at each side of the endless conveyor, the support for said plate comprising triangular standards 25 supported on the forward ends of the side rails 5 as shown in Figs. 1 and 3 with a cross shaft 26 having end trunnions 27 journaled in the upper ends of the bracket. A longitudinally extending rod 28 threaded at its opposite ends as at 29 with a screw rod 28 disposed at each side of the endless conveyor is threaded at its forward end in the cross shaft 26 while the rear threaded end thereof freely passes through a bracket 30 carried by the outer side of the adjacent side bar 7 of the conveyor frame, adjusting nuts 31 threaded on the rear end of the screw rod 28 and opposite sides of the bracket 30 being operable to hold the screw rod in adjusted position when the desired angularity of the conveyor frame is attained. In raising or lowering the conveyor frame, the nuts 31 are loosened or operated to be spaced from the bracket 30, and at which time the rear upper end of the endless conveyor may be raised or lowered by the screw rod 15 and at which the nuts 31 are tightened to engage the angle bracket 30 as a further support for the upper elevated end of the conveyor. A series of hooks 32 carried by the outer face of each guard plate 24 engage the screw rod 29 for freely suspending the guard plates theron. It will therefore be seen that the upper ends of the guard plates 24 are raised and lowered simultaneously with the vertical adjustment of the rear upper end of the endless conveyor. As shown in Fig. 3, a transverse guard rail 33 extends between the lower forward ends of the spaced guard plates 24 and is anchored at its opposite ends as at 34 to said plate and in proximity to the lower upper side of the endless conveyor belt 12 to prevent downward discharge of snow deposited upon the endless belt by the gathering drum 19.

The operating mechanism for the endless conveyor and gathering drum 19 includes the motor 35 illustrated by dotted lines in Fig. 1 having a gear and sprocket chain connection 36 with the cross shaft 37 journaled at its ends in the side rail 5, the sprocket wheel 38 fixed to the shaft 37 between the side bars 1 and rails 5 being aligned with the sprocket wheel 14 at the upper end of the conveyor and over which sprocket wheels 38 and 14 the sprocket chain 39 passes. As shown in Fig. 1, the bearing support 37 for the sprocket wheel 38 is in sufficiently close proximity to the hinge support 10 for movement of the endless conveyor

frame to occasion only a slight amount of slack in the chain 39 when the upper end of the conveyor is lowered; however, should it be found necessary, any well known means may be associated with the chain 39 to compensate for any slack appearing therein. The cross shaft 40 journaled in the side rails 5 carries a gear 41 meshing with the gear 42 upon the shaft 37 and said gear 41 is in mesh with the gear 43 upon the shaft 44 journaled in the side rails 5. Each projecting end of the shaft 44 carries a sprocket wheel 45 alined with the sprocket wheels 23 associated with the snow gathering drum 19 and over which sprocket wheels the sprocket chains 46 pass. It will therefore be seen that the motor 35 operating the several meshing gears drives the endless conveyor belt 12 and rotates the snow gathering drum 19.

From the above detailed description of the invention, it is believed that the construction and operation thereof will at once be apparent, it being understood that a collection receptacle or vehicle trails the snow gathering apparatus, and while there is herein shown and described the preferred embodiment of the present invention, it is nevertheless to be understood that minor changes may be made therein without departing from the spirit and scope of the invention as claimed.

What is claimed as new is:

1. In snow gathering apparatus, a vehicle frame, an endless conveyor hingedly supported thereon intermediate its ends, a rotatable gathering drum at the forward lower end of the conveyor and means for operating the conveyor and drum and snow guard plates supported on the frame at opposite sides of the lower end of the conveyor, the support for the guard plates including standards at the forward end of the frame, a cross shaft journaled between the standards, longitudinally adjustable screw rods engaging the cross shaft at their forward ends and supported at their rear ends on the opposite sides of the conveyor and hooks carried by the guard plates for suspending the same on the screw rods.

2. In snow gathering apparatus, a vehicle frame, an endless conveyor hingedly supported thereon intermediate its ends, a rotatable gathering drum at the forward lower end of the conveyor and means for operating the conveyor and drum, and snow guard plates supported on the frame at opposite sides of the lower end of the conveyor and a guard rail extending between the spaced guard plates in proximity of the lower end of the conveyor and anchored at its ends to the guard plates, the support for the guard plates including standards at the forward end of the frame, a cross shaft journaled between the standards, longitudinally adjustable screw rods engaging the

cross shaft at their forward ends and supported at their rear ends on the opposite sides of the conveyor and hooks carried by the guard plates for suspending the same on the 5 screw rods.

3. In snow gathering apparatus, a vehicle frame, an endless conveyor hingedly supported thereon intermediate its ends, a rotatable gathering drum at the forward lower 10 end of the conveyor and means for operating the conveyor and drum and snow guard plates supported on the frame at opposite sides of the lower end of the conveyor, the support for the guard plates including 15 standards at the forward end of the frame, a cross shaft journalled between the standards, longitudinally adjustable screw rods engaging the cross shaft at their forward ends and supported at their rear ends on the 20 opposite sides of the conveyor and hooks carried by the guard plates for suspending the same on the screw rods and a screw rod having threaded engagement with the vehicle frame rearwardly of the pivotal mounting 25 of the conveyor and a ball and socket connection between the upper end thereof and the conveyor whereby the rear end of the conveyor may be raised and lowered on its hinged support.

- 30 4. In snow gathering apparatus, a ve-

hicle frame, an endless conveyor hingedly supported thereon intermediate its ends, a rotatable gathering drum at the forward lower end of the conveyor and means for operating the conveyor and drum, and snow 35 guard plates supported on the frame at opposite sides of the lower end of the conveyor and a guard rail extending between the spaced guard plates in proximity to the lower end of the conveyor and anchored at 40 its ends to the guard plates, the support for the guard plates including standards at the forward end of the frame, a cross shaft journalled between the standards, longitudinally adjustable screw rods engaging 45 the cross shaft at their forward ends and supported at their rear ends on the opposite sides of the conveyor and hooks carried by the guard plates for suspending the same on the screw rods and a screw rod having 50 threaded engagement with the vehicle frame rearwardly of the pivotal mounting of the conveyor and a ball and socket connection between the upper end thereof and the conveyor whereby the rear end of the conveyor 55 may be raised and lowered on its hinged support.

In testimony whereof I affix my signature.

JAMES O'BRIEN.
